[57] CLAIM

The ornamental design for a spike for a shoe, as shown and described.

DESCRIPTION

FIG. 1 is a perspective view of a shoe sole spike showing our new design in use;

FIG. 2 is a right side elevational view thereof;

FIG. 3 is a perspective view;

FIG. 4 is an inverted front elevational view;

FIG. 5 is an inverted rear elevational view;

FIG. 6 is a bottom plan view;

FIG. 7 is a top plan view;

FIG. 8 is a right side elevational view thereof; and,

FIG. 9 is a left side elevational view thereof.

The broken line showing of a shoe in FIGS. 1 and 2 is for illustrative purposes only and forms no part of the claimed design.
